(57) **CLAIM**

The ornamental design for a curved, slatted hammock, as shown and described.

DESCRIPTION

FIG. 1 is a perspective view of a curved, slatted hammock, showing my new design;

FIG. 2 is a side elevational view thereof, the side opposite being identical;

FIG. 3 is a top plan view thereof;

FIG. 4 is a bottom plan view thereof; and,

FIG. 5 is an end elevation view thereof, the end opposite being identical.

The broken line showing of hammock suspension cables is for illustrative purposes only and forms no part of the claimed design.
